UNITED STATES PATENT OFFICE.

HERBERT L. THOMPSON, OF ELGIN, ILLINOIS.

POWER WHEEL.

Application filed August 27, 1921. Serial No. 496,090.

To all whom it may concern:

Be it known that I, HERBERT L. THOMPSON, a citizen of the United States, and a resident of the city of Elgin, in the county 5 of Kane and State of Illinois, have invented certain new and useful Improvements in Power Wheels, of which the following is a specification.

My invention relates to a rotary water 10 motor of the impact type and its object is to provide a simple, inexpensive device of this class which can be operated by a stream or jet of small volume but relatively high velocity to develop a considerable amount 15 of power. The small amount of water used per unit of time makes it possible to enclose the rotary water wheel in a small, compact housing. The wheel itself may be made quite small relative to the power 20 which it develops so that the friction at its bearings is reduced to a minimum.

The motor is shown in the drawing as used for operating a culinary beater but is not claimed herein in that connection, the 25 motor in combination with the beater being claimed in a co-pending application filed as a division hereof November 19, 1921, as Serial No. 516,275. This application is concerned solely with the motor as such which 30 might be put to various different useful purposes.

In the drawing

Fig. 1 is a vertical sectional view of the motor shown as forming a part of the 35 beating apparatus of my co-pending application above referred to.

Fig. 2 is a plan view of the device with the motor wheel housing broken away to show the wheel, and

Fig. 3 is a view, in perspective, of the wheel.

Referring to the drawing, the wheel 24 is shown as secured to the upper end of a shaft 15, which shaft has an upper bearing 21, 22 and a lower bearing 16 in stationary beating member 4. The shaft is shown as provided with a rotary beating element 18, 19, 20 and projects into a jar 9 secured to a cap 6 which is riveted at 13 45 to the under side of the water wheel casing 26, 26^a, the parts of which are beaded together at 27. 28 is a thimble extending into the top of the casing and provided with a union for attaching the casing to the down turned end of a water faucet, for example. 50 Thimble 28 is formed with a relatively

small jet orifice 29 for directing a jet of water across the wheel 24 in a plane substantially parallel to the plane of the wheel. 55 33 is a water discharge pipe leading from the casing and 37 a small opening in the top of the casing to prevent the formation of a vacuum in the casing.

The water wheel consists preferably of a sheet metal disc 24 which is slit along preferably substantially straight lines oblique at acute angles to radii of the disc from the periphery of the disc inwardly to points spaced from its center, with the portions of the disc between the periphery and the 70 slits bent up to provide vanes A, B, C, D, E and F. These vanes are preferably curved transversely with respect to their length so as to provide water receiving surfaces which are concave, that is, approximately semi-tubular.

In operation the water jet from aperture 29, which is of small diameter but of considerable velocity, impinges against the concave faces of the vanes so as to impart 80 rotary movement to the wheel, the jet being centered on the vanes because of their transversely concave contour. The stream of water impinging on each of the vanes is directed thereby across the open center of 85 the wheel to the vane next but one beyond the vane of first impingement, the deflected jet impinging upon the concave surface of such other vane so as to give an additional forward rotary impulse to the wheel. That 90 is, the water flowing from vane A passes across the wheel and impinges upon vane C. When the vane F is struck upon by the jet the stream deflected therefrom impinges against B and so on. The transversely concave contour of the vanes keeps the water jet impinging on the vanes from spreading and dissipating its force. Because of the small volume of water employed per unit of time the housing of the water wheel may 100 be made small and compact.

I claim:

1. A rotary impact water motor comprising a wheel, means for directing a jet of water across the wheel in a plane substantially parallel therewith, and a series of vanes on said wheel in the path of the jet having transversely concave water receiving surfaces and extending from the periphery of the wheel inwardly to points spaced from the axis thereof at such an angle to each other that water impinging on each

- vane is deflected therefrom across the central space between the vanes and against another vane in the direction to impart a forward impulse of rotation to the wheel.
5. 2. A rotary impact water motor comprising a wheel, means for directing a jet of water across the wheel in a plane substantially parallel therewith, and a series of vanes arranged on one face of the wheel in 10 the path of the jet and extending along substantially straight lines from the periphery of the wheel inwardly to points spaced from the axis thereof at such angles to each other that water impinging on each vane is deflected therefrom across the central space 15 between the vanes and against another vane in the direction to impart a forward rotary impulse to the wheel.
3. A rotary impact water motor comprising a wheel, means for directing a jet of water across the wheel in a stream substantially parallel therewith, and a series of vanes on said wheel in the path of said jet and extending along substantially 20 straight lines from the periphery of the wheel inwardly to points spaced from the axis thereof at acute angles to the radii of the wheel whereby water impinging on each vane is deflected therefrom across the central 25 space between said vanes and against another vane in the direction to impart a forward rotary impulse to the wheel.
4. A rotary impact water motor comprising a disc which is slit on lines extending outwardly from points spaced from the center of the disc with the portions between the edge of the disc and the slits bent outwardly to form vanes, and means for directing a jet of water across the disc against 30 said vanes.
5. A rotary impact water motor comprising a disc which is slit on lines oblique to the radii of the disc and extending outwardly from points spaced from the center of the disc with the portions between the edge of the disc and the slits bent outwardly to form vanes, and means for directing a jet of water across the disc against said vanes.
6. A rotary impact water motor comprising a disc which is slit on lines extending outwardly from points spaced from the center of the disc with the portions between the edge of the disc and the slits bent outwardly on a curve to form vanes having transversely concave water receiving surfaces, and means for directing a jet of water 45 across the disc against said vanes.
7. A rotary impact water motor comprising a disc which is slit on lines oblique to the radii of the disc and extending outwardly from points spaced from the center of the disc with the portions between the edge of the disc and the slits bent outwardly on a curve to form vanes having transversely concave water receiving surfaces,

and means for directing a jet of water across the disc against said vanes.

8. In a rotary impact water motor, the combination of a wheel consisting of a single disc provided on one side with a series of 70 vanes extending inwardly from the periphery of the disc to points spaced from the center thereof, said vanes being formed on straight lines in the direction of their length but curved transversely thereto to provide 75 transversely concave water receiving surfaces, and means for directing a jet of water against said surfaces.

9. In a rotary impact water motor, the combination of a wheel consisting of a single 80 disc provided on one side with a series of vanes extending inwardly from the periphery of the disc on substantially straight lines oblique to radii of the disc to points spaced from the center thereof and curved 85 transversely with respect to the length of the vanes to provide concave water receiving surfaces, and means for directing a jet of water against said surfaces.

10. In a rotary impact water motor, the combination of a casing which is relatively thin vertically in proportion to its horizontal dimensions and is provided with a water discharge opening, a thimble projecting vertically into said casing at one end and 90 formed with a substantially horizontal jet orifice, and a wheel horizontally disposed in the other end of said casing comprising a disc provided on one face with a series of 95 vanes extending from the periphery of the disc inwardly on lines substantially oblique to radii of the disc to points spaced from the center of the disc and projecting into the path of said jet.

11. In a rotary impact water motor, the combination of a casing which is relatively thin vertically in proportion to its horizontal dimensions and is provided with a water discharge opening, a thimble projecting vertically into said casing at one end and 100 formed with a substantially horizontal jet orifice, and a wheel horizontally disposed in the other end of said casing comprising a disc provided on one face with a series of 105 vanes extending from the periphery of the disc inwardly on lines substantially oblique to radii of the disc to points spaced from the center of the disc and projecting into the path of said jet and curved transversely 110 with respect to their length to provide concave water receiving surfaces.

12. A rotary impact water motor comprising a wheel, means for directing a jet of water across the wheel in a plane substantially parallel therewith, and a series 115 of vanes on said wheel in the path of said jet and extending from the periphery of the wheel inwardly to points spaced from the axis thereof at such angles to each other that the water impinging upon each vane is de- 120

flected therefrom across the central space between the vanes and against another vane in the direction to impart a forward impulse of rotation to the wheel, the space at 5 the middle of the wheel between the vanes being unobstructed so as to permit the jet to pass across at any point.

13. A rotary impact water motor comprising a wheel, means for directing a jet of 10 water across the wheel in a plane substantially parallel therewith, and a series of vanes on said wheel in the path of said jet and extending from the periphery of the wheel inwardly to points spaced from the

axis thereof at such angles to each other that 15 the water impinging upon each vane is deflected therefrom across the central space between the vanes and against another vane in the direction to impart a forward impulse of rotation to the wheel, each of said 20 vanes comprising means for centering the jet thereon.

In witness whereof, I have hereunto set my hand this ninth day of August, 1921.

HERBERT L. THOMPSON.
